LIGHT PROJECTING DEVICE

Filed Sept. 1, 1925

Inventor:
Cromwell A.B. Halvorson Jr.

by *Alfred S. Knott*
His Attorney.

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHT-PROJECTING DEVICE.

Application filed September 1, 1925. Serial No. 53,905.

My invention relates to light projecting devices, and in particular to devices of this sort which are especially adapted for use in connection with traffic signaling.

5 Traffic signals as ordinarily constructed do not admit of adjustment and for that reason it is not feasible to use standard devices at street intersections where the streets do not cross each other at right angles, or where the 10 streets do not run directly into one another.

It is an object of my invention to provide a light projecting device adapted for use as a traffic signal in which the light projecting element may be adjusted so that the 15 beam may be shifted from one position to another. With a device of this character a standard equipment becomes more flexible and is adapted to be more readily used under varying conditions.

20 The features of my invention will be readily understood from the following specification and drawing, in which Fig. 1 shows a traffic signal in elevation comprising three sections, each section having a number of light projecting elements and comprising the features of 25 my invention. Fig. 2 shows one of the sections in perspective. In this figure one of the light projectors is shown in position. Fig. 3 shows one of the projectors in section. Fig. 30 4 is a rear view of the projector in Fig. 3.

Referring more in detail to the drawing, it will be seen that the unit shown in Fig. 1 is mounted upon a pedestal 2. The unit is provided with a canopy 3 and with three intermediate sections 4, 5, and 6. One of these sections is shown in Fig. 2 enlarged and in perspective. In Fig. 2 one of the light projectors is shown in position and tilted. By referring to Fig. 3 it will be seen that the 40 projector comprises a reflector element 7. This reflector is provided with a rear opening through which the socket 8 for supporting the light bulb projects. The reflector is also provided with a front opening through which the rays which go to make up the beam pass forward. The rear portion of the reflector immediately around the rear opening and extending some distance is in the form of a 45 surface of revolution and may be paraboloidal, for example. Beyond the paraboloidal region and extending as far as the 50 region 9, appears the section 10 which is also in the form of a surface of revolution, spherical, for example. The portion of the reflector 11 to the right of the ridge 9 is also

in the form of a surface of revolution, and also may be spherical. Beyond the spherical region 11 the reflector is provided with a flaring portion 12 which is also in the form of a surface of revolution, and may be paraboloidal.

55 The holder for the reflector comprises a collar 13 which is adapted to be secured to one of the sections, such as the section in Fig. 2, by any suitable means, such as the screws 14. The holder is provided with a rearwardly projecting flange 15, from which the spider arms 16 project rearwardly, the ends of which are resiliently drawn together by means of a coiled spring 17. The reflector is nested within a flaring collar 18 to the forward portion or neck, of which the hood 19 and the front glass 20 are suitably secured. The collar 18 serves as a bearing for the reflector which slides within the opening of the 70 collar 13. The reflector is provided at the rear with a cap 21 which is provided with an opening through which the socket 8 projects and to which the socket is clamped by means of a clamping band 22. The collar section 23 75 of the cap is provided with a number of incisions to enable the band 22 to draw the collar 23 tightly about the socket. It will be seen that the cap 21 is provided with a hood 24 80 which is integral with the cap 21, and which serves as a resilient member; and against which the ends of the spider arms 16 rest and slide when the unit is being adjusted.

85 With the construction described it will be seen that the holder for the reflector is in the nature of what may be termed an eye ball socket, within which the reflector and its collar 18 hood 24 and cap 21 slide. The support is in the nature of a universal joint so that the reflector may be tilted as indicated 90 in Fig. 2, or in any other position about the axis of the support within certain limits. Therefore, the beam may be lowered, or shifted to the right or to the left, or to any intermediate position within a limited range 95 determined by the size of the opening of the collar 13. It will be understood that the socket 8 has sufficient room within the circle formed by the spring 17 to allow the reflector to be adjusted without having the socket 100 strike the spring.

105 Therefore, a unit of the type shown in Fig. 1 may be used at an intersection where the streets do not intersect at right angles, inasmuch as the light projecting elements may be 110

shifted to one side so that the axis of the projecting element may fall in the same plane with a line down the center of the street.

It will be seen, therefore, that the reflector is mounted upon one of the elements of a ball and socket joint and so supported that the axis of the reflector may be caused to describe a cone. Furthermore, the reflector is so mounted that it may be rotated about its own axis. It will be further seen that the reflector is in the nature of a surface of revolution having a major diameter in the proximity of the ridge 9, and that the socket supports the reflector along regions on either side of the major diameter.

While I have described my invention in connection with a device of specific construction as illustrated, it will be understood that I do not wish to be limited to this specific construction, inasmuch as, in view of the specification and disclosure, variations and modifications may be readily constructed which do not depart from the spirit of the invention nor from the scope of the claims.

25 What I claim as new and desire to secure by Letters Patent of the United States, is:

1. In a light projector, a reflector, a ball and socket joint structure, said reflector being mounted within the ball element of said structure whereby the reflector may be adjusted by adjusting said ball element, said reflector having the general contour of a focalizing surface, and having a maximum diameter along a plane transverse the axis of the reflector, said reflector having also a front bearing surface about the opening of the reflector on one side of said plane and a rear bearing surface about the axis of the reflector on the opposite side of the plane, said bearing surfaces constituting the ball element of the said structure, resilient elements projecting rearwardly from the socket element, arranged about the axis of the reflector and converging toward said axis and a resilient member engaging the ends of said resilient elements nearest the axis of the reflector for holding the reflector in place in the socket element.

2. In combination, a focalizing reflector substantially globular in form having a rear opening and a front opening, the axis of the

reflector extending through both of said openings, a bearing element in the form of a collar covering the front region of the reflector about the front opening, a separate and additional bearing element covering the rear region of the reflector about the said rear opening, a socket for supporting the reflector and its bearings, and means for clamping the reflector in said socket between said bearing elements.

3. In combination, a focalizing reflector substantially globular in form having a rear opening and a front opening, the axis of the reflector extending through both of said openings, a bearing element in the form of a collar covering the front region of the reflector about the front opening, a separate and additional bearing element covering the rear region of the reflector about the said rear opening, a socket for supporting the reflector and its bearings, and resilient means for clamping the reflector in said socket between said bearing elements.

4. In a light projector, in combination, a support, a frame, said frame being anchored to said support, a ball reflector, said reflector having a focalizing region and having an axis of projection passing through said region, a light source mounted within said focalizing region, a bearing for the ball on said frame formed about an opening in said support and about an axis through said opening, a portion of said ball extending through said opening said axis of projection also extending through said opening and strips of resilient material each having one end anchored to said frame, said strips being disposed about said bearing and about said reflector, each spring having a free end and a ring in the form of a coiled spring in latching engagement with the free ends of said springs, operating to draw said springs toward said reflector and operating to maintain the latter pressed in its bearing, said reflector being free to move in its bearing whereby a cone may be described with its axis about said first mentioned axis.

In witness whereof, I have hereunto set my hand this 29th day of August, 1925.

CROMWELL A. B. HALVORSON, JR.
